FRED WALTON BACON, OF NEW HAVEN, CONNECTICUT.

Design No. 4,095, dated June 7, 1870.

DESIGN FOR A SEAL OR BANNER.

The Schedule referred to in these Letters Patent and making part of the same

To all whom it may concern:

Be it known that I, FRED WALTON BACON, of the city and county of New Haven, and State of Connecticut, have originated and designed a new Device for a Badge, Banner, or Seal of the Order of Knights of Pythias, of which the following is a full, clear, and exact description, reference being had to the accompanying drawings making a part of this specification.

The border of the design, B B B, indicates the walls of a fortification or citadel.

The helmet h,
Death-head d,
Cross-lances c c c c,
Flaming torch f,
Sprig of myrtle s,
Open book b,
Shield S S, with the initial letters marked thereon, are all emblems of the order of Knights of Pythias.

The dotted outlines O O O indicate the form of the frame of design.

The space between the said outline O O O and the border B B B may be used for the lettered inscriptions when the design is used for a seal.

Claim.

What I claim as my invention, and desire to secure by Letters Patent, is—

The design for badge, banner, or seal of the order of Knights of Pythias herein set forth, the same being made of any metals or materials, plain or in colors.

FRED WALTON BACON.
